UNITED STATES PATENT OFFICE.

CHAUNCEY M. MURCH, OF CINCINNATI, OHIO.

IMPROVEMENT IN REFLECTORS.

Specification forming part of Letters Patent No. 149,778, dated April 14, 1874; application filed March 21, 1874.

To all whom it may concern:

Be it known that I, CHAUNCEY M. MURCH, of Cincinnati, Hamilton county, Ohio, have invented a new and useful Reflector for Lamps and Burners, of which the following is a specification:

My device is designed for ready attachment to any ordinary gas-burner or lamp; and comprises a pair of V-formed wings or reflectors, which, being secured upon suitable wire supports or brackets, are capable of adjustment so as to divert the light in two opposite directions in equal or unequal proportions, or wholly in either direction, at will.

Figure 1 is a perspective view, showing my reflectors applied to a common gas-burner and set for directing the rays equally in two opposite directions. Fig. 2 shows the reflectors applied to a coal-oil lamp, the wings being set to project the light wholly in one direction. Fig. 3 represents one of the reflectors detached from the supporting-bracket, a portion being broken away. Figs. 4 and 5 are plans, showing different positions of the reflectors.

A may represent a gas-burner, and B a kerosene-lamp of common construction. C are

wire brackets, adapted to be secured to the burner by means of jaws *c* and slides *c'*, or otherwise. The brackets *C* have upturned extremities *c''*, which enter sockets *d* in my reflectors, composed each of two similar concave wings or blades, *D D'*, having the represented V form in their horizontal section. These two duplex reflectors may be set so as to project the light equally in both directions, as in Fig. 1, or more largely in one direction, as in Fig. 4, or wholly either forward or backward, as in Figs. 2 and 5. Diagram X shows one of the reflectors placed on its bracket in reversed position. The reflectors may be so constructed that when thus reversed they will completely inclose the light.

I claim as new—

The pair of V-shaped reflectors *D D'*, constructed with sockets *d* in the angles, and supported adjustably on the brackets *C*, substantially as and for the purpose set forth.

In testimony of which invention I hereunto set my hand.

Attest: CHAUNCEY M. MURCH.
